DESIGN FOR A RECEIVER EARPIECE

Albert E. Woodruff, Oak Park, Ill., assignor to
Automatic Electric Laboratories, Inc., Chicago,
Ill., a corporation of Delaware

Application November 29, 1944, Serial No. 116,598

Term of patent 14 years

(Cl. D26—14)

To all whom it may concern:

Be it known that I, Albert E. Woodruff, a citizen of the United States, residing at Oak Park, in the county of Cook, in the State of Illinois, have invented a new, original, and ornamental Design for a Receiver Earpiece, of which the following is a specification, reference being had to the accompanying drawing, forming a part thereof.

Figure 1 is a front view of a receiver earpiece, showing my new design,

Figure 2 is a back view thereof,

Figure 3 is a side view thereof taken looking toward the left hand side of Figure 1,

Figure 4 is a side view thereof taken looking toward the bottom of Figure 1,

Figure 5 is a side view thereof taken looking toward the right hand side of Figure 1,

Figure 6 is a longitudinal section taken in the direction of the arrows 6—6 of Figure 1,

Figure 7 is a lateral section taken in the direction of the arrows 7—7 of Figure 1, and

Figure 8 is a longitudinal section taken in the direction of the arrows 8—8 of Figure 1.

I claim:

The ornamental design for a receiver earpiece, substantially as shown.

ALBERT E. WOODRUFF.
